(57) CLAIM

The ornamental design for a memorabilia lamp, as shown and described.

DESCRIPTION

FIG. 1 is a top, front, and left side perspective view of a memorabilia lamp showing my new design;

FIG. 2 is a rear elevational view thereof, with the broken-line disclosure of football memorabilia being shown for illustrative purposes only and forming no part of the claimed design;

FIG. 3 is a top plan view thereof;

FIG. 4 is a bottom plan view thereof;

FIG. 5 is a side elevational view thereof; and,

FIG. 6 is an opposite side elevational view thereof.
